CLAIM

(21) Appl. No.: **29/285,274**

The ornamental design for an operator control panel with display and multiple function buttons for a storage library, as shown and described.

(22) Filed: **Mar. 26, 2007**

DESCRIPTION

(51) **LOC (9) Cl.** 14-02

FIG. 1 is a front perspective view of a first embodiment of an operator control panel with display and multiple function buttons for a storage library;

(52) **U.S. Cl.** D14/313

FIG. 2 is a front end view of FIG. 1;

(58) **Field of Classification Search** D14/300,
D14/301, 308, 388, 349–361; D13/162,
D13/184, 199; 312/223.1–223.3; 360/99.01–99.12;
361/690–696; 369/34.01, 36.01; 358/496

FIG. 3 is a rear end view of FIG. 1;

See application file for complete search history.

FIG. 4 is a side view of FIG. 1;

(56) **References Cited**

FIG. 5 is a top view of FIG. 1;

U.S. PATENT DOCUMENTS

FIG. 6 is a front perspective view of a second embodiment operator control panel with display and multiple function buttons for a storage library;
